UNITED STATES PATENT OFFICE.

JOHN W. THOMAS, JR., OF NASHVILLE, TENNESSEE.

RAILWAY SWITCH AND SIGNAL INTERLOCKING MECHANISM.

SPECIFICATION forming part of Letters Patent No. 468,160, dated February 2, 1892.

Application filed August 12, 1891. Serial No. 402,425. (No model.)

To all whom it may concern:

Be it known that I, JOHN W. THOMAS, Jr., of Nashville, in the State of Tennessee, have invented certain new and useful Improvements in Railway Switch and Signal Interlocking Mechanism, of which the following is a specification.

My invention has reference to the interlocking mechanism which usually is located in the tower from which the different signals, switches, and switch-locking devices of the system controlled by the operator in the tower are actuated by means of suitable levers and intermediate motion-transmitting devices.

15 The improvements I have devised relate, principally, to the devices by which the various levers are interlocked, my object being to cheapen, simplify, and enhance the efficiency of the apparatus, and to so organize and combine the operative parts thereof as to obtain a mechanism by the aid of which a three-position signal can be handled with ease and perfect safety. These improvements will first be described by reference to the drawings accompanying this specification, and will then be more particularly pointed out in the claims.

20 The improvements are applicable as well to machines or apparatuses in which special locking is required as to those termed by signal-engineers "straight-locking machines;" but in the main figures of the drawings I have represented my invention as embodied in a machine of the latter class—viz., a straight-locking machine.

25 In the drawings, Figure 1 is a front elevation, on reduced scale, of so much of the machine as needed for the purposes of explanation. In this figure, owing to the smallness of the scale, it is possible to represent only 30 the general relation in which the several operative parts stand to one another. Fig. 2 is a similar elevation of the machine on enlarged scale, parts of the machine between the two ends being broken away, so as to admit the 35 remaining parts to be brought together on an adequate scale on one sheet. Fig. 3 is a transverse vertical section of the machine through one of the signal-levers. Fig. 4 is a similar section through one of the switch or point locking levers. Fig. 5 represents in side elevation the several locking yokes and pins em-

ployed in the particular organization represented in the preceding figures. Fig. 6 is a diagram of the system of tracks, signals, and switches for which the machine is intended. 55 Fig. 7 is a diagram of the locking-bars illustrating the working of the apparatus. Figs. 8 to 16 are modifications which will be hereinafter more particularly referred to.

Confining attention for the present to the main figures of the drawings, Figs. 1 to 7, inclusive, X, Y, and Z are the operating-levers in the tower of ordinary or suitable construction and provided, as usual, with quadrants 1. Bolted to the frame-work of the 60 tower are cast-iron floor-plates 3, having in them suitable openings for the passage of the operative parts of the mechanism, and upon these floor-plates and at the opposite ends of the machine are bolted the upright guide- 65 plates 4. The levers X, which are at the ends of the machine, are the signal-levers. The levers Y Z are located in the intermediate portion of the machine, and of these levers those marked Y are the switch-levers and 70 those marked Z are the switch-point-locking levers. The point-locking mechanism is not shown, being a well-known device and forming no part of my invention. It is a device which customarily is located within a few 75 feet of the switch itself, and consists, usually, of a pair of plungers, one or the other of which locks the switch according as the points are normal or reversed; as will be understood, for example, by reference to British Letters 80 Patent No. 1,064 of 1874 or United States Patent No. 369,815, to Harry Roser, dated September 13, 1887. The levers are hung in brackets 2, secured to the frame-work of the tower. The short arms of the signal-levers X (usually 85 about two feet long) are forked at the end, so as to straddle links 6, and they engage the links by pins which pass through their forked ends and through slots 5 in the links, there being one link for each lever. Each link is 90 fulcrumed at 7 to a casting 8, and to its upper end is jointed a yoke 9, armed with locking-pins 10, which are keyed or otherwise suitably secured to it.

In and through the guide-plates 4, opposite 100 the points where the pins of the several yokes come, are holes in which the pins work and

through which they can pass to locking-bars 15, which extend the entire length of the machine and are mounted upon the guide-plates 4 on the side or face thereof opposite that on 5 which the locking yokes and pins are in such manner as to be capable of sliding horizontally or in the direction of their length. These locking-bars are provided with holes which, when they are brought opposite to or in register with the holes in the guide-plates, can be entered by the locking-pins 10, and thus the locking-bars can be locked in position. There is one locking-bar 15 for each switch. The arrangement of the holes in the locking-bars 15 is such that they can be entered or engaged by the locking-pins of that yoke only which pertains to a signal-lever the switch and point locking levers appropriate to which have first been properly operated to set and lock the 20 switch for which the signal is to be set.

To the vertical connecting-rod 11 of each lever Z, for working facing point locks or switch and lock movements, is attached a pipe-plug 12, which is connected to one arm of a 25 bell-crank 13 by a connecting-rod 14. The bell-crank is pivoted in a suitable standard, and has its other arm pinned to the lock-bar 15 appropriate to the switch, which is controlled by lever Z.

30 In lieu of bell-cranks I can employ obliquely slotted motion-plates, (devices well known in the art to which this invention pertains,) which should be secured to the vertical connecting-rods 14 and be engaged by pins on their appropriate locking-bars.

At the lower end of the slot 5 of each link 6 is an offset s, which, when acted on by the pin in the forked end of the signal-lever X, serves to give the link its forward throw (for 40 the purpose of engaging its locking-pins 10 with the locking-bars 15) at the very commencement of the movement of lever X, and the part of the slot 5 above the offset s is so curved that when the link has been thus thrown it will be an arc of a circle, having the fulcrum of lever X as a center. The result is that a quick movement of the yoke and pins 10 is obtained at the commencement, so that by the time the hand-lever X, 45 in being reversed from its normal position in Fig. 3, shows a movement of about five-eighths of an inch on the quadrant (which in practice does not affect the position of the signal) its locking-pins have been forced into engagement 50 with the appropriate locking-bars 15, thus locking all the switches over which the signal about to be lowered gives a train a right to pass when the signal is lowered, and by this time the pin of the hand-lever has reached 55 the curved portion of the slot 5 of the link above the offset, and for the remainder of the throw of the lever the locking mechanism consequently remains unaffected and at rest. Consequently ample time is left after the locking to operate with ease and certainty a three-position signal before the lever completes its throw. In other words, after the lever has

operated through the offset s the interlocking mechanism it has still a range of movement amply sufficient to permit it to set the signal to either "caution" or "safety."

In practice there is only one-eighth of an inch clearance between the inner ends of the locking-pins 10 and the locking-bars 15, and it is therefore evident that, unless the switches over which the signal to be lowered gives a train a right to proceed are properly set, so as to bring the holes in the bars 15 opposite to the pins 10, the hand-lever which operates that signal cannot be moved. On returning the 80 signal-lever X from either one of these two last named positions to normal or danger position the locking-pins 10 remain stationary and in locking position until the lever has very nearly reached its normal position, at 85 which time, by the action of the lever on the offset s, the locking-pins are disengaged and withdrawn from the locking-bars 15, thus permitting the signal-man to unlock and throw any of the switches he may desire. 90

The manner of operating the levers X Y Z is as follows: When a switch is set and locked in its normal position, the levers occupy the position shown in Figs. 3 and 4. To reverse the switch, the point-lock lever Z is first pulled back one-half stroke, which movement withdraws one of the locking-plungers of the lock located at the switch itself. Then the switch-lever Y is pulled back full-stroke, with the effect of reversing the points of the unlocked switch. Then the point-lock lever Z is pulled back the other half of its stroke, with the effect of locking the switch by the other locking-plunger of the lock located at the switch. Then, and only then, can the signal-lever X appropriate to the switch be operated, because it is only by the movement of the lever Z that the lock-bar 15 appropriate to the switch has been shifted to bring it into position where it may be engaged by the interlocking-yoke 9 of the signal-lever, and the bar cannot be brought to this position until the switch has not only been completely set, but also completely locked. Obviously the lock-bars 15 can be operated from the switch-lever Y, instead of from the point-lock lever Z; but this in practice would be a modification to be employed only in the absence of special point-lock mechanism and levers. In any event they should be connected to and operated by some part of the switch-controlling mechanism, whether the mechanism for shifting or the mechanism for locking the switches or switch-points. 110

In the system represented in the drawings 125 there are six locking-bars and eight signal-levers X. There are consequently eight yokes 9. In all of these yokes some of the pins are long, while others are short. The long pins alone are locking-pins, and these alone have 130 the designating numeral 10. The shorter pins have no functions other than by entering the holes in the guide-plates 4 to serve as guides to assist in assuring the yokes in position dur-

ing their back-and-forth movement. It will also be noted that the long pins or locking-pins proper on the several yokes vary in position. This is made necessary by the interlocking scheme and by the fact that all of the yokes do not engage the same locking-bars.

Fig. 6 is a diagram of the system of tracks, signals, and switches to which the machine above described is applicable. In this figure there are three tracks and six switches, viz: three cross-over switches marked 1, 2, and 3, respectively, one derail and two plain switches marked 5 and 6, respectively, and nine signals marked A to I, inclusive. While there are nine signals there are only eight signal-levers X, Fig. 1; but this is because the signals G and H are supposed to be operated from one and the same signal-lever through a "selector." Switch 5 has to be reversed to get either one of the two signals; but both signals cannot be lowered at the same time.

In Fig. 7 the locking-bars are represented diagrammatically in normal position. The lines lettered A to I, inclusive, which intersect the bars 15, are the center lines of the locking-pins 10 of the yokes 9, which pertain to the signal-levers appropriate to the signals which bear similar letters in diagram Fig. 6, and upon each one of the locking-bars is indicated the particular switch of Fig. 6 to which that bar belongs. Wherever the same two letters—as, for example, A A—appear in juxtaposition on any locking-bar, it indicates that a hole in the locking-bar is in register or in line with the locking-pin appropriate to it. A single letter in full lines—as, for example, F—by the side of a hole (or a small circle typical of that hole) indicates that the hole is out of register with its pin, and a single dotted letter—as, for example F—inside of a dotted circle indicates the pin with which the similarly-lettered hole is out of register.

The mode of operation of the apparatus will be readily understood from these diagrams with but little further explanation. Indeed, the movements required in order to clear the several signals can be conveniently tabulated as follows, the column headed "Normal" containing those locking-bars which occupy normal position (shown in Fig. 7) and the column headed "To the left" containing those locking-bars which are moved or shifted to the left of normal position:

	Normal.	To the left.
To clear signal A.....	Bar 1	.....
To clear signal B.....	Bars 3 and 4.....	5.....
To clear signal C.....	Bars 3, 4, and 5.....	.....
To clear signal D.....	Bars 1, 4, and 5.....	3.....
To clear signal E.....	Bars 1, 3, and 5.....	.....
60 To clear signal F.....	Bars 1 and 6.....	3 and 4.....
To clear signal G.....	.....	6.....
To clear signal H.....	.....	6.....
To clear signal I.....	Bars 2, 4, and 6.....	.....

To explain this table, if it be desired to clear signal A, for example, this can be done without any movement of the locking-bars from normal. The yoke 9 of the signal-lever

appropriate to signal A has but one locking-pin 10, Fig. 5, which engages only the first or top locking-bar. To clear the signal F, the first and sixth locking-bars remain at normal and the third and fourth locking-bars are shifted to the left of normal so as to bring their holes F in line with the locking-pins indicated by the dotted letters F. As soon as this is done all of the holes F in the first, third, fourth, and sixth locking-bars will be in line with each other and in register with the locking-pins of the yoke 9 of the lever appropriate to signal F. This yoke is shown in Fig. 5. It has four-locking-pins, which come opposite the holes in the first, third, fourth, and sixth locking-bars. Its second and fifth pins, however, are short and do not engage the second and fifth locking-bars. I may remark here that the short pins are not indispensable. They can be omitted, if desired, and they appear only because as a matter of economy and to save multiplication of patterns I cast all the yokes in one mold with teeth or pins of uniform length and then break off or otherwise shorten the proper ones of these teeth, according to the particular location in which the yoke is to be used.

From the foregoing table and the diagrams to which it refers it will be observed that when the combination for one signal is made the combination for all other signals which may conflict is broken. In doing this only such switches are locked as a lowered signal gives a train a right to pass over, and those switches which the train does not go over in following the signal are left free to be used, thus allowing the signal-man to lower any number of signals which do not give conflicting routes.

I have hereinbefore stated that my improvements are applicable not only to straight-locking machines, such as illustrated in the figures of the drawings already referred to, but also to machines in which special locking is required. For example, in the case of a single track having, say, east and west bound signals the two can be so interlocked that when either is lowered to "safety" the other must remain at "danger." This is effected by providing the locking pin or pins of the yoke of each lever—the east-bound-signal lever and the west-bound-signal lever—with side lugs having recesses and by combining these with a sliding dog, which is operated by said projections and acts to lock one or the other of the yokes, as the case may be, by engaging their pin or pins, the mechanism in other respects remaining the same as already described by reference to the previous figures. Such a modification is represented in Figs. 8 and 9. Fig. 8 is a horizontal section through a guide-plate 4, one of the locking-bars 15, and the yokes 9 of the east and west bound signal levers in the plane of one of the locking-pins 10 of each of said yokes. Fig. 9 is a rear elevation of these parts with the yokes removed and the locking-pins in cross-section.

Each yoke is to be connected by its own slotted link (similar to the link 6 already described) to its own independent signal-lever. To the back of the guide-plate 4 is held a horizontally-sliding dog 16 by the head of a bolt, which screws into the back of the guide-plate and passes through a slot in the dog of such length as to permit to the dog the necessary range of movement. The pins 10 of the yokes 5 also pass through openings in the dog, and on the inner opposite edges of these openings are beveled projections marked 26 and 27, respectively. The two pins 10 have each a lateral lug or projection 25 and 30, respectively, in each of which is formed a beveled recess 28 and 29 to match the beveled projection 26 or 10 27 on the dog 16, with which it is to co-operate. In Fig. 8 the parts are shown in normal position with the lock-bar adjusted to bring its 15 holes in register with the holes in the guide-plate through which the locking-pins work. If now it be desired to lower the east-bound signal, the lever appropriate to that signal is of course operated. By the time the lever 20 shows five-eighths of an inch travel on its quadrant (which in practice does not affect the position of its signal) the lug 25 of locking-pin 10 of the east-bound signal will be opposite to and in contact with the bevel 26 of dog 16, thus holding the bevel 27 of the dog 25 in the beveled notch or recess 28 of the locking-pin of the west-bound signal, and consequently preventing this signal from being operated. If, on the other hand, assuming the 30 parts to be again in normal position, as in Fig. 8, it is desired to lower the west-bound signal, the bevel 26 of dog 16, by the inwardly-moving pin of the west-bound signal, is forced into the beveled notch 29 of the locking-pin 35 of the east-bound signal and is held there until the west-bound signal is again restored to its normal position.

A variation of the special locking plan last described, designed by me more particularly 40 with reference to the interlocking of home and distance signals and involving the use of links having two offsets which give successive impulses to the locking-pins during the movement of the signal-lever, as well as the use of 45 locking-pins having each a number of lateral projections and beveled notches and recesses, is illustrated in Figs. 10 to 14, inclusive.

Fig. 10 is a side elevation of the link 6^x to be used with the home-signal lever. This 50 link in no wise differs from the link shown in Fig. 3, save that, in addition to an offset *s* at the lower end of its slot 5, it has a second offset *s'* at or near the upper end of said slot. I remark here that the link used with the distance-signal lever need have but one offset *s*, or, in other words, it may be just like the single offset-link in Fig. 3. The throw given by the single offset of the one link is about equal to the throw given by the combined action of 60 the two offsets of the other link; but of course a two-offset link can be used for the distance-signal, if desired.

Fig. 11 is a section similar to Fig. 8, hereinbefore described, except that the sliding dog and the locking-pins differ in detail in 70 the two figures.

Figs. 12, 13, and 14 are sections similar to Fig. 11, representing the parts in the position which they successively assume during the operation of reversing the home and distance 75 signal levers.

Corresponding reference numbers and letters in Figs. 11 and 8 indicate corresponding parts. The sliding dog 16^x in Fig. 11 is like the dog 16 in Fig. 8, provided with beveled projections opposite the pins; but in Fig. 11 these bevels are not upon the interior opposite edges of the openings through which the pins pass; but one of them 22 is upon the inner edge of one opening and the other 22^x is upon the 80 outer edge of the other opening. Upon one side of the home-signal locking-pin 10, adjoining the bevel 22 on the dog, are two similar beveled recesses 20 and an intermediate projection 23, and on the opposite side of the 85 pin is a wedge projection 17, which works in an opening formed for it in the guide-plate 4 and never passes back out from the dog 16^x, even when its yoke 9 is fully retracted. Upon the side of the distance-signal locking-pin 90 next to the bevel 22^x on the dog are two similar beveled notches or recesses 18 and an intermediate projection 18^x, and upon the opposite side of this pin is a wedge projection 19, which normally is back and outside of the 95 dog 16, and when its pin moves forward never passes in beyond the dog. The two wedge 100 projections 17 and 19 have their bevel in opposite directions. They both operate to move or slide the dog in the same direction; but 105 the projection 17 only so operates when its pin is drawn out, while conversely the projection 19 only so operates when its pin is pushed in. The parts in normal position are 110 shown in Fig. 11, in which position the projection 17 on the locking-pin of the home-signal holds the bevel 22^x of the dog in the inner notch 18 of the locking-pin of the home-signal, and thus locks the latter in place. The parts are so organized and arranged that 115 in bringing the home-signal to safety position the home-signal lever must be fully reversed before the distance-signal is fully unlocked. For example, in reversing the home-signal lever for this purpose, when that lever 120 shows one-fourth of an inch travel on its quadrant the locking-pin 10 of the home-signal yoke, actuated by the lower offset *s* of link 6^x, will have moved about five-eighths of an inch, bringing the parts to the position 125 shown in Fig. 12, with the bar 15 locked and the edge 21 of the dog forced and held immovably against the locking-pin 10 of the distance-signal by the projection 23 on the home-signal pin. As the operator continues the 130 movement of the home-signal lever, the locking-pin 10 of said lever remains stationary until the concluding portion of the stroke, when the top offset *s'* in the link 6^x further

advances the home-signal locking-pin 10, which movement of the pin brings its outer notch 20 opposite to the bevel 22 of the dog. The parts in this position are shown in Fig. 13. Then, and only then, is the locking-pin 10 of the home-signal released. The next move is to reverse the distance-signal lever, the effect of which is to bring the distance-signal locking-pin 10 to the position shown in Fig. 14. It will be seen from the above that until the movement of the home-signal is completed it is impossible to lower the distance-signal. When the home-signal is in normal position, the distance-signal is locked by the projection 17 on home-signal pin drawing and holding the bevel 22^x of the dog in the inner notch 18^x of the distance-signal pin. After this first advance of the home-signal pin and while the silent movement of the lever is taking place (by "silent movement" I mean that portion of the movement of the lever during which it passes through the curved portion of slot 5 between the two offsets s and s') projection 23 on the home-signal pin is in contact with bevel 22 of the dog, thus pressing and holding the edge 21 of the dog up against the distance-signal pin, so that with the home-signal in this position if the operator should try to lower his distance-signal he would be prevented from so doing by the bringing up of the lug or projection 19 on the distance-signal pin against the dog. Consequently until the completion of the movement of the home-signal lever, which brings the parts to the position shown in Fig. 13, it is impossible to lower the distance-signal. When after this the distance-signal is lowered, bringing the parts to the position shown in Fig. 14, it will be seen that the projection 19 on the distance-signal locking-pin holds the bevel 22 of the dog in the outer notch 20 of the home-signal locking-pin, and thus the distance-signal must be restored to its normal position before the home-signal can be operated.

The link with an offset at the top and at the bottom of the slot, as illustrated in Fig. 10, is to be used where a two-position signal is to be handled by the lever connected to the link, there being first an active, then a silent, and then an active movement, and the object of having the second offset at the top of the slot being that the signal-man must fully reverse the lever before the second active movement occurs. If, however, it is desired to handle a three-position signal, then the link should be modified, as shown in Fig. 15—that is to say, the second offset s' should be about midway of the slot. This form of link during the throw of the lever connected to it gives in succession an active, a silent, an active, and a silent movement, the second active movement occurring just as the lever reaches its middle position and the signal-blade reaches an angle of forty-five degrees. With a link of this description the stroke of the locking-pins 10 is completed when the signal is in

"caution" position, after which the lever can be put to "safety" position without disturbing them. If, for example, a three-position 70 home-signal and a distance-signal are to be handled, a link like that in Fig. 15 is connected to the home-signal lever, and the releasing of the distance-signal is completed when the home-signal lever is in its middle 75 position, (at which time the home-signal is in "caution" position.) As the releasing occurs when the home-signal is in this position, a train can be allowed to proceed under "caution-signal" or the home-signal lever can be 80 reversed fully and the train proceed under a "safety-signal," as the occasion may demand. The foregoing illustrations will suffice to show the ease with which any desired combination of special locking can be applied to 85 the machine.

It will be noticed that in the machine illustrated in the main figures of the drawings there are spaces only for six locking-bars; but the capacity of each or any locking-bar can 90 be doubled by cutting it in two lengthwise and forming semicircular recesses in its meeting edges, which conjoined will form a hole into which the locking-pin can enter, so as to lock both bars. This construction is indicated 95 in Fig. 16, which is a face view of a portion of a locking-bar so divided. In case it is not necessary to lock both bars by the same pin the bar that does not require to be locked can be slotted, as indicated by the dotted line in 100 Fig. 16.

Having described my improvements and the best way now known to me of carrying the same into effect, I state in conclusion that I do not restrict myself to the details herein 105 shown and described, for manifestly the same can be varied in many particulars without departure from the spirit of the invention; but

What I claim herein as new and of my own invention is as follows:

1. The combination of sliding locking-bars connected to and actuated by the switch-controlling mechanism, locking-pins to engage the selected bar or bars, slotted vibratory links carrying said pins and provided in their 115 slots with offsets which determine the throw of the pins, and signal-levers connected to and adapted to operate the links, substantially as and for the purposes hereinbefore set forth.

2. The combination of a pivoted link having a curved slot provided with an offset, a signal-lever having a pin which works in the slot of the link, a locking pin or pins carried by the link, a guide-plate provided with apertures in which said pins work, one or more locking-bars provided with corresponding apertures and movable to bring said apertures into and out of register with those of the guide-plate, as desired, and switch-controlling 125 mechanism connected to and adapted to operate the lock-bars, the combination being and acting substantially as hereinbefore set forth.

3. The combination of two independently-movable locking-pins or sets of locking-pins provided each with lateral locking recesses and projections, as described, locking-bars to be engaged by said pins, a sliding dog actuated by said pins during their movement and adapted to lock and release the same at the times and in the manner substantially as stated, and a separate lever and slotted link connection for each of said locking-pins or sets of locking-pins, substantially as and for the purposes hereinbefore set forth.
4. In interlocking switch and signal mechanism, the combination, with locking-pins and locking-bars with which said pins co-operate, of a pivoted pin-carrying link having a slot provided with two offsets s s' , and an operating-lever provided with a stud which works in the slot and acts upon said offsets successively to cause the intermittent movement in one direction or the other of the link and locking-pins during the throw of the lever,

substantially as and for the purposes hereinbefore set forth.

5. In an interlocking switch and signal machine, the combination, with the signal-actuating mechanism and the signal and switch interlocking mechanism, of a signal-lever and a pivoted link connected on the one hand to the signal-lever by a pin-and-slot connection and on the other hand to the interlocking mechanism, whereby the signal-lever during its throw is enabled to actuate the interlocking mechanism and also to operate the signal as a three-position signal, substantially as and for the purposes hereinbefore set forth.

In testimony whereof I affix my signature in presence of two witnesses.

JOHN W. THOMAS, JR.
